[57] CLAIM

The ornamental design for an exterior surface configuration of an automobile front light assembly, as shown and described.

DESCRIPTION

FIG. 1 is a front view of an exterior surface configuration of an automobile front light assembly according to our novel design;

FIG. 2 is a side view of an exterior surface configuration of an automobile front light assembly according to our novel design;

FIG. 3 is a top partly perspective view of an exterior surface configuration of an automobile front light assembly according to our novel design; and,

FIG. 4 is a perspective view taken from the front and left side of an exterior surface configuration of an automobile front light assembly according to our novel design.

Features shown in dash lines depict the environment and do not form part of the claimed design.
